UNITED STATES PATENT OFFICE.

HUGO HEIMANN, OF ST. LOUIS, MISSOURI.

DESIGN FOR A DISPLAY-CABINET.

No. 39,210.

Specification for Design.

Patented March 17, 1908.

Application filed February 8, 1907. Serial No. 356,491. Term of patent 14 years.

To all whom it may concern:

Be it known that I, HUGO HEIMANN, a citizen of the United States, and a resident of the city of St. Louis and State of Missouri, have invented a new, original, and ornamental Design for Display-Cabinets, of which the following is a specification.

The figure is a perspective view of a display cabinet showing my new design.

What I claim is:

The ornamental design for a display cabinet, as shown.

HUGO HEIMANN.
